UNITED STATES PATENT OFFICE.

RUDOLPH KALKUSCH, OF CHICAGO, ILLINOIS.

FIRE ESCAPE.

1,441,438.

Specification of Letters Patent.

Patented Apr. 4, 1922.

Application filed September 25, 1919. Serial No. 326,225.

To all whom it may concern:

Be it known that I, RUDOLPH KALKUSCH, a citizen of the United States, and a resident of the city of Chicago, county of Cook, 5 and State of Illinois, have invented certain new and useful Improvements in Fire Escapes, of which the following is a specification.

My invention relates to new and useful 10 improvements in fire escapes, and has for its object the provision on a fire escape of a counterbalancing means beneath the stairway and free from interference with the supporting platform, although beneath and 15 close to it. Another object is to provide a counterbalance effective along the center line of the stairway without causing it or its supporting parts to project lower than said stairway, when in its normal position, 20 to any appreciable extent.

Other objects will appear hereinafter.

The invention consists in the combinations and arrangements of parts hereinafter described and claimed.

25 The invention will be best understood by reference to the accompanying drawings forming a part of this specification, and in which,

Fig. 1 is a side elevation of the lower 30 section of a fire escape embodying my invention.

Fig. 2 is a sectional view taken on substantially line 2—2 of Fig. 1, with the stop for the counterbalance removed.

35 Fig. 3 is a rear view of my invention with parts in section.

The approved form of construction comprises the lower section 4 of a fire escape, the upper end of which is pivotally connected, as at 5, in the usual manner to the usual stationary support or platform 6.

Pivotally connected at one end to the member 6, as at 7, is a depending link 8, the lower end of which is pivotally connected to a shoe 10 which is rigidly mounted to the bar or beam 11. To the outer end of the member 11 is mounted the weight 12. The opposite end of the member 11 is securely fastened to a member 13, which has 45 extending laterally from its opposite ends lugs 14 by means of which the member 13 is pivotally connected to the opposite sides of the stairway by a cooperating rod 15. Secured to the rearward end of the member 50 6 is a U-shaped member 16 in which the member 11 is adapted to move vertically

relatively to the platform 6. My invention relates solely to the lower section of a fire escape which is usually in the form of a stairway pivotally supported at its upper 60 end and counterbalanced so that it may be supported normally in horizontal position at about the level of its pivot, whereby it is elevated above the street and presents no obstruction to pedestrians or vehicles. 65 Local regulations often provide a minimum clearance between the side-walk or street and the pivoted stairway, when in its normal or horizontal position. Since it is desirable to have the pivoted stairway 70 fairly low, the stairway is usually designed so that the clearance beneath it shall be as small as the ordinances will allow. To this end, it has been customary in many cases to provide an extension on one side of the 75 stairway, to the outer end of which the counterbalance is secured. The counterbalance and the extension therefor project no lower than the main body of the stairway, when in horizontal position. This 80 arrangement, however, whereby the counterweight is supported from one side of the stairway (it being impractical, under some circumstances, to support it from both sides), produces a tendency in the stairway to sag on one side, with a consequent weakening at the point of pivotal connection of the stairway with the support. This 85 tendency is objectional and is only partially offset by providing a very stiff, rigid, and consequently more expensive construction.

Where attempts have been made heretofore to arrange the counterweight in the vertical plane passing through the center line of the stairway, the required parts projected down, so as to necessitate an objectionably high location of the supporting platform.

In my invention I have eliminated the side strain on the stairway and have also 100 provided a means whereby the weight projects a very slight distance below the stairway, when in its normal or horizontal position. As clearly shown in Fig. 2, the bar or beam 11 is secured intermediate the sides 105 of the stairway 4, that is, it is beneath and in the vertical plane of the longitudinal center line of the stairway, and as a result the stairway is supported at its main axis, and the stairway consequently has no skewing 110 tendency. As shown in the dotted portion of Fig. 1, the bar or beam 11 diverges from

the stairway when the same is lowered, but when the stairway is raised, the bar 11 is drawn inwardly, so as to lie parallel to the stairway. This is due to the fact that the 5 distance from the pivotal point 15 to the pivotal point of the lower end of the link 8 is substantially the same as the distance from the pivotal point 15 to the pivotal point 5. It will be noted, as a result of the 10 foregoing construction, that, when the stairway is lowered, the counterweight clears the landing or platform 6, the bar 11 diverging from the stairway and being spaced from it at one end a considerable distance. When 15 the stairway has swung upwardly in horizontal position, however, the bar 11 is substantially parallel with the side members of the stairway 4, the fulcrum point at the lower end of the member 8 having swung 20 to the dotted line position, and the counterweight being disposed only slightly below the platform. Under these circumstances, it will be seen that, if the distance from the counterweight to the ground is the 25 minimum required clearance, the distance from the stairway proper to the ground is only a few inches greater. The supporting member or platform 6 may, therefore, be located as close to the ground as permissible 30 or as necessary. It is also to be noticed that, upon lowering the stairway from its horizontal or normal position, the link 8 is moved backwardly toward the rear of the platform 6. The member 16, upon the stairway 35 being raised to its horizontal or normal position, engages the under surface of the member 11 and prevents the stairway 4 from being raised above a horizontal position.

40 In order to prevent skewing or the objectionable side twist it is not essential that the counterweight or its support be mounted along the center line of the stairway, as long as the resultant forces are applied centrally to the stairway.

While I have illustrated and described the preferred form of construction for carrying my invention into effect, this is capable of variation and modification without departing from the spirit of the invention. I, therefore, do not wish to be limited to the precise details of the construction set forth, but desire to avail myself of such variations and modifications as come within the scope 55 of the appended claims.

Having described my invention, what I claim as new and desire to secure by Letters Patent, is:—

1. A fire-escape comprising a stairway 60 pivotally mounted at its upper end on a support so as to swing alternately into in-

clined and substantially horizontal position; counterbalancing means operatively connected with said stairway; and means pivotally connected with said support and said 65 counterbalancing means for automatically causing said counterbalancing means to take a substantially horizontal position close beneath said support and said stairway when the latter is swung into such horizontal position, substantially as described. 70

2. A fire-escape comprising a stairway hinged at its upper end to a support; a link pivoted to swing from said support; and a counterbalancing lever pivotally connected intermediate its ends with the depending end of said link, one end of said lever being operatively connected with said stairway, and the other bearing a counterweight, substantially as described. 75

3. A fire escape comprising a platform; a stairway hinged at its upper end to said platform; a link pivotally connected with said platform and swingingly depending therefrom; a lever pivotally connected at 85 one of its ends with said stairway, and intermediate its ends with the depending end of said link; and a counter-weight on the other end of said lever to raise and support the stairway in horizontal position, substantially as described. 90

4. A fire escape comprising a platform, a link mounting pivoted to said platform and depending therefrom; a lever pivoted intermediate its ends to said link mounting 95 and operatively connected at one end with said stairway, the distance between the pivotal connection of said lever with said stairway and its pivotal connection with said mounting, and the distance between said lever and stairway pivotal connection and the pivotal connection between said stairway and said platform, being approximately equal; and a counterweight on the other end of said lever, substantially as described. 100

5. In a fire escape, a supporting member; a stairway, normally in horizontal position, pivotally connected to said member and adapted to be inclined downward relatively to said member; counter-balancing means 110 secured to said stairway and so supported as to lie adjacent to said stairway when in horizontal position, and to diverge therefrom when the same is downwardly inclined, substantially as described. 115

In testimony whereof I have signed my name to this specification in the presence of two subscribing witnesses.

RUDOLPH KALKUSCH.
